ABSTRACT: An improved storage apparatus includes a plurality of drawers or trays which are slidably mounted on a pair of storage racks. The storage racks are spaced apart and face or open toward each other so that a carriage can open a closed drawer by pulling it outwardly of one of the storage racks while simultaneously therewith closing an open drawer by pushing it into the other storage rack. The carriage is advantageously moved between the storage racks by a cable drive assembly.

STORAGE APPARATUS

The present invention relates generally to a storage apparatus and more particularly to a storage apparatus which includes a plurality of drawers or trays for holding material to be stored and a carriage for opening and closing the drawers.

It is an object of this invention to provide a new and improved apparatus for compactly storing materials on trays or drawers which are movable between a closed condition for storing the materials and an open condition to enable materials to be removed from and deposited into the drawers.

It is another object of this invention to provide a new and improved storage apparatus which includes a pair of rack assemblies for holding a plurality of drawers which are movable between open and closed conditions and a carriage which is movable between the rack assemblies to close an open drawer of one of the rack assemblies while simultaneously therewith opening a closed drawer of the other rack assembly.

It is another object of this invention to provide a new and improved storage apparatus in accordance with the next preceding object wherein the carriage assembly is moved relative to the rack assemblies by operation of a cable drive arrangement.

It is another object of this invention to provide a new and improved apparatus for storing materials in a pair of rack assemblies disposed in a spaced apart relationship and opening toward each other, a plurality of drawers slidably mounted in each of the rack assemblies for movement between a closed condition within the rack assemblies and an open condition extending outwardly from the rack assemblies, and a carriage means which is movable in a first direction along a track extending between the rack assemblies to move a drawer associated with one of the rack assemblies to the closed condition while simultaneously therewith moving a drawer associated with the other rack assembly toward the open condition.

These and other objects and features of the invention will become more apparent upon a consideration of the following description taken in connection with the accompanying drawings wherein:

FIG. 1 is a partially broken away perspective view of a material storage apparatus constructed in accordance with the present invention;

FIG. 2 is a partially broken away plan view of the storage apparatus of FIG. 1, illustrating the relationship between a storage assembly for holding drawers of material and a carriage for opening and closing the drawers;

FIG. 3 is an enlarged sectional view of a coupling for connecting a drawer of the storage assembly of FIG. 2 with the carriage;

FIG. 4 is an enlarged elevational view, taken generally along a line 4-4 of FIG. 3, further illustrating the relationship between the coupling and the carriage, the coupling being shown in solid lines in a locked or engaged condition and in dashed lines in a released or unlocked condition;

FIG. 5 is a broken away schematic illustration of a cable drive arrangement for moving the carriage relative to the storage assembly; and

FIG. 6 is a broken away sectional view of a support and guide roller arrangement for a drawer or tray of the storage assembly of FIG. 2.

A material storage apparatus 10 forming a specific preferred embodiment of the present invention is illustrated in FIG. 1 and includes a pair of substantially identical storage assemblies 12 and 14 which are spaced apart and face or open toward each other. The storage assembly 12 includes a rack assembly or framework 18 and a plurality of substantially identical drawers or trays 20 which are movable between a closed condition vertically aligned within the rack assembly 18 and an open condition in which they extend out of the rack assembly. The storage assembly 14 is of the same construction as the storage assembly 12 and includes a rack assembly or framework 24 for supporting a plurality of drawers 26. A car-

riage or buggy 30 is movable along floor mounted tracks or rails 32 and 34 to move the drawers 20 and 26 between the open and closed conditions.

To provide for efficient operation of the material storage apparatus 10, the carriage 30 is operable to close an open drawer of one storage assembly while simultaneously therewith opening a closed drawer of the other storage assembly. If it is assumed that the carriage 30 is moving toward the left as viewed in FIG. 1, a drawer or tray 20a is being pushed into the rack assembly 18 by the carriage 30 to move the drawer 20a from the open condition to the closed condition. At the same time, a drawer 26a is being pulled out of the storage assembly 14 to move the drawer 26a from the closed condition to the open condition to provide access to material 38 stored therein. Of course, movement of the carriage 30 toward the right, as viewed in FIG. 1, would result in the drawer 20a being moved to the open condition while the drawer 26a is closed. Thus, efficient operation of the material storage apparatus 10 is promoted by the ability of the carriage 30 to open one drawer while closing another.

When the drawer 20a has been moved to the closed condition by the carriage 30, the carriage is disconnected from the drawer 20a by operating a coupling assembly 42 from an engaged or latched condition, illustrated in solid lines in FIGS. 3 and 4, to a released or disengaged condition, illustrated in dashed lines in FIG. 4. Another coupling assembly 42 mounted on the next one of the drawers 20 to be opened is then operated to the engaged or latched condition of FIG. 3. Subsequent rightward movement of the carriage 30 results in the selected drawer 20 being pulled to the open condition. A coupling assembly 42 is mounted on a forward or outer end member 46 of each of the drawers 20 and 26 so that each of the drawers can be separately connected to the carriage 30 and moved between the open and closed conditions. Of course, the drawers 20 are connected to the left side of the carriage 30 (as viewed in FIG. 1) while the drawers 26 are connected to the right side of the carriage.

Although it is contemplated that many different types of coupling assemblies could be used to connect the drawers 20 and 26 to the carriage 30, the illustrated coupling assembly 42 includes a pair of generally U-shaped connector members 48 which are pivotally connected at 50 on the front member 46 of an associated drawer. The generally U-shaped connector member 48 (see FIGS. 2 and 4) are pivotally interconnected by actuator rods 54 and 56. When the actuator rod 56 is pulled toward the left as viewed in FIG. 4, the connector member 48 is pivoted in a generally counterclockwise direction from the latched or retaining position shown in solid lines in FIG. 4 to the released position shown in dashed lines in FIG. 4. The second connector member 48 of the coupling assembly 42 is simultaneously pivoted to the released condition by movement of the actuator rod 54. A suitable retaining means 60 (see FIG. 2) is mounted on the front member 46 of the drawer to retain the actuator rod 56 against movement.

When it is desired to move a drawer 20 to the open condition, the carriage 30 is moved toward the storage assembly 12 until support bars or members 64 mounted on the carriage are disposed immediately beneath the front members on the drawers 20 (see FIG. 3). The coupling assembly 42 on the selected drawer is then operated to the engaged condition by merely releasing the associated actuator rod 56. The center of gravity of each of the connector members 48 is disposed outwardly of the pivot connection 50 and causes the connector members to swing downwardly to the latched condition. An inner arm 66 on each of the connector members is then disposed immediately inside the front member 46 of the selected drawer while an outer arm 68 of the connector member is disposed forwardly of the support member 64 on the carriage 30. Subsequent movement of the carriage 30 toward the right as viewed in FIGS. 1 and 2 moves the support member 64 into abutting engagement with the arm 68 and enables the selected drawer 20 to be pulled outwardly toward the open condition.

As the selected drawer 20 is opened, a previously opened one of the drawers 26 is closed by the movement of the carriage 30. If one of the drawers 26 is to be opened, the carriage 30 is moved to the right (as viewed in FIG. 1). Once the carriage 30 is adjacent to the storage assembly 14, the coupling assembly 42 on the selected drawer 26 is latched to an associated one of the support members 64 on the side of the carriage closest to the storage assembly 14, i.e., the right side as viewed in FIG. 1. The carriage 30 is then moved toward the left, as viewed in FIG. 1, to open the selected drawer 26 while closing a previously open one of the drawers 20.

The carriage 30 is moved relative to the tracks 32 and 34 to open and close selected ones of the drawers 20 and 26 by operation of a drive assembly 70 (see FIGS. 1 and 5). The drive assembly 70, in the illustrated embodiment of the invention, includes a cable drum 72 which is rotated by operation of an electric motor and gear reduction unit 74 mounted on the carriage 30. The electric motor in the unit 74 is connected with a suitable source of power by a flexible conductor 76 (see FIG. 1). Suitable controls 78 are mounted on the storage assembly 14 to control the operation of the drive assembly 70. A cable 80 is secured at opposite ends to the floor adjacent to outer end portions of the storage assemblies 12 and 14, only one of the connections being illustrated at 84 in FIG. 2. The cable 80 is wound around the drum 72 so that upon rotation of the drum 72 the carriage 30 is moved along the tracks 32 and 34. When the drum 72 is rotated in a clockwise direction as viewed in FIG. 5, the drum moves along the cable 80 to move the carriage 30 toward the right. Conversely, when the drum 72 is rotated in a counterclockwise direction as viewed in FIG. 5, the carriage is moved toward the left.

During outward movement of a selected drawer 20 toward the open condition, side rails 88 and 90 of the drawer are supported by suitable rollers 92 mounted on upright frame members or posts 94 of the rack assembly 18 (see FIGS. 2 and 6). Although only one support roller 92 has been shown in FIG. 6, a plurality of support rollers are mounted on each post 94 to provide adequate support for the drawers 20 (see FIG. 2). In addition, guide rollers 96 (FIG. 6) engage the side rails 90 on the selected drawer to prevent binding or cocking of the drawer as it is being moved relative to the rack assembly 18. It should be noted that the provision of a pair of connector members 48 in each of the coupling assemblies 42 further promotes an even movement of the drawer 20 outwardly without cocking or binding. This is because the coupling assemblies 42 interconnect two spaced apart portions of the carriage 30 and the selected drawer.

Once a selected drawer 20 has been moved to the open condition, the forward end portion of the drawer is supported on one of the support members 64 on the carriage 30 (see FIGS. 1 and 3) while the inner or trailing end of the drawer is supported by rollers 92 mounted on the forward or outer posts 94 of the rack assembly 18. The distance between the storage assemblies 12 and 14 is somewhat less than the combined length of the drawer 20 and the length of the carriage 30, indicated at 100 in FIG. 2, so that substantially the entire length of the drawer is exposed to provide easy access to the material 38 while preventing the drawer from being pulled completely out of the rack assembly 18. A ladder 104 is advantageously provided on the carriage 30 so that an operator can readily climb onto and open one of the upper drawers 20 or 26 to secure a chain or other suitable connecting means from an overhead crane (not shown) to the material 38 or to assist in releasing material to be deposited in the drawer by the overhead crane.

Once the desired material 38 has been removed from and/or additional material has been deposited in the open drawer 20, the operation of the drive assembly 70 is reversed to close the drawer 20 and open a selected one of the drawers 26. During this inward movement, the drawer 20 is positioned or centered relative to the posts 94 of the rack assembly 18 by engagement of cam sections 108 (FIG. 2) on the inner end of the drawer 20 with the guide rollers 96. When the drawer 20 reaches the closed condition, an actuator member 112 on the carriage 30

actuates a limit switch 114 to interrupt operation of the drive assembly 70. In addition, a stop member 118 (FIG. 2) on the drawer 20 engages one of the posts 94 to stop the inward movement of the drawer. Although the construction and operation of the storage assembly 14 has not been set forth herein as fully as has the construction and operation of the storage assembly 12, it should be understood that their constructions and operations are the same.

In view of the foregoing remarks, it can be seen that the material storage apparatus 10 includes a pair of rack assemblies 18 and 24 which open toward each other and are adapted to hold a plurality of drawers or trays 20 and 26. The drawers 20 and 26 are movable between a closed condition within the rack assemblies and an open condition extending outwardly from the rack assemblies by a carriage 30 which moves along tracks 32 and 34 under the influence of a cable drive assembly 70. The carriage is movable from a position adjacent one of the storage assemblies, for example the storage assembly 14, to a position adjacent the other storage assembly, for example the storage assembly 12, to move an open drawer 20 to the closed condition within the rack assembly 18 and to simultaneously therewith move a closed drawer 26 to the open condition extending outwardly from the rack assembly 24. Of course, movement of the carriage 30 in the opposite direction will move a drawer 20 to the open condition and/or close one of the drawers 26.

Although the drawers 20 and 26 have been illustrated herein as being adapted to hold generally flat sheets of material 38, it should be understood that the drawers could be adapted to store many different types of materials such as containers or pipes. In addition, it is contemplated that other known couplings could be substituted for the specific coupling assembly 42 disclosed herein. It is also contemplated that the construction of the cable drive assembly 70 may be varied, for example a rack and pinion drive might be used to move the carriage 30 relative to the storage assemblies 12 and 14.

Having described a preferred embodiment of my invention, the following I claim:

1. Apparatus for storing materials, said apparatus comprising a pair of rack assemblies disposed in a spaced apart relationship and opening toward each other, a plurality of drawers in each of said rack assemblies for holding materials, said drawers being movable between a closed condition within said rack assemblies and an open condition extending outwardly from said rack assemblies, and carriage means movable between said rack assemblies for moving an open drawer of one of said rack assemblies toward the closed condition and for simultaneously therewith moving a closed drawer of the other rack assembly toward the open condition.

2. Apparatus as set forth in claim 1 further including drive means for moving said carriage means relative to said rack assemblies, said drive means including cable means having one end portion fixedly secured adjacent to said one rack assembly and an opposite end portion fixedly secured adjacent to said other rack assembly, a cable drum mounted on said carriage means, and motor means mounted on said carriage means for rotating said cable drum, said cable means extending around said cable drum whereby rotation of said cable drum by said motor means moves said carriage means relative to said rack assemblies.

3. Apparatus as set forth in claim 1 wherein said carriage means includes means for supportingly engaging outer end portions of said drawers while said drawers are in the open condition, said rack assemblies being spaced apart by a distance which is less than the combined extent of one of said drawers and said carriage means in a direction parallel to their direction of movement whereby inner end portions of said drawers are supported by said rack assemblies when said drawers are in a fully open condition.

4. Apparatus as set forth in claim 1 further including a first set of coupling means for selectively connecting the drawers in said one rack assembly to one side of said carriage means and a second set of coupling means for selectively connecting the

drawers in said other rack assembly to the opposite side of said carriage means.

5. Apparatus as set forth in claim 1 further including ladder means mounted on said carriage means for enabling an operator of said apparatus to have ready access to materials stored in upper ones of said drawers when they are in the open condition.

6. Apparatus as set forth in claim 1 further including track means extending between said rack assemblies for guiding movement of said carriage means.

7. Apparatus for storing materials, said apparatus comprising a pair of rack assemblies disposed in a spaced apart relationship and opening toward each other, a plurality of drawers slidably mounted in each of said rack assemblies for movement between a closed condition within said rack assemblies and an open condition extending outwardly of said rack assemblies, track means extending between said rack assemblies, carriage means movable between said rack assemblies by said track means, a first coupling means for connecting a selected one of the drawers in one of said rack assemblies with one side of said carriage means, a second coupling means for connecting a selected one of the drawers in the other of said rack assemblies with a side of said carriage means opposite from said one side, and drive means connected to said carriage means and operable in a first direction to move said carriage means along said track means toward said one rack assembly and away from said other rack assembly to move a drawer connected to the one side of said carriage means by said first coupling means toward the closed condition within said one rack assembly and to simultaneously therewith move a drawer

30

connected to the opposite side of said carriage means by said second coupling means toward the open condition extending outwardly from said other rack assembly, said drive means being operable in a second direction to move said carriage means along said track means toward said other rack assembly and away from said one rack assembly to move a drawer connected to the one side of said carriage means by said first coupling means toward the open condition extending outwardly from said one rack assembly and to simultaneously therewith move a drawer connected to the opposite side of said carriage means by said second coupling means toward the closed condition within said other rack assembly.

8. Apparatus as set forth in claim 7 wherein said drive means includes a motor and cable drum mounted on said carriage means and cable means fixedly secured adjacent to said rack assemblies at opposite end portions and extending around said cable drum, said motor being connected with said cable drum and operable to rotate said cable drum to thereby effect movement of said carriage means relative to said rack assemblies.

9. An apparatus as set forth in claim 7 wherein said first and second coupling means are each operable to interconnect said carriage means and a selected drawer at two locations along the front of the drawer to promote even movement of the drawer relative to the associated rack assembly.

10. An apparatus as set forth in claim 7 further including ladder means mounted on said carriage means for enabling an operator of said apparatus to reach material stored in uppermost ones of said drawers.
